UNITED STATES PATENT OFFICE.

WILLIAM S. HAMM, OF HUBBARD WOODS, AND ROGER M. NEWBOLD, OF CHICAGO, ILLINOIS, ASSIGNORS TO THE ADAMS & WESTLAKE COMPANY, OF CHICAGO, ILLINOIS, A CORPORATION OF ILLINOIS.

DESIGN FOR AN AUTOMOBILE-LAMP.

42,083.

Specification for Design.

Patented Jan. 9, 1912.

Application filed September 7, 1911. Serial No. 648,247. Term of patent 14 years.

To all whom it may concern:

Be it known that we, WILLIAM S. HAMM and ROGER M. NEWBOLD, citizens of the United States, residing at Hubbard Woods and Chicago, respectively, in the county of Cook and State of Illinois, have invented a new, original, and ornamental Design for Automobile-Lamps, of which the following is a specification, reference being had to the accompanying drawing, forming a part thereof.

In the drawing Figure 1 is a side elevation of the lamp; and Fig. 2 is a plan view thereof.

The distinctive characteristics of the design are as follows:—The body portion of the lamp is rectangular in form, and is surrounded by a rectangular dome of less cross-sectional area than the body, the lower portion of the dome having vertical walls and its upper portion tapering inward. The base of the dome is surrounded by a breast

which tapers upwardly. The dome is surrounded by a cap of greater width than the apex of the dome, this cap being rectangular in form. The base of the lamp extending downwardly from the body portion is rectangular and of less size than the body, its upper portion being surrounded by a breast tapering downwardly.

We claim—

The ornamental design for an automobile lamp, as shown and described.

WILLIAM S. HAMM.
ROGER M. NEWBOLD.
